WINDOW CLEANING MECHANISM

Waclaw Narajowski, New York, N.Y.

Application October 10, 1950, Serial No. 189,361

7 Claims. (Cl. 15—220)

1

This invention relates to window cleaning devices and more particularly to new and improved mechanism which facilitates the efficient cleaning of both sides of a window pane simultaneously.

It has been found that window-cleaning devices utilizing magnetically coupled leader and follower members for operating on both sides of a window pane at the same time, such as disclosed in the pending United States patent application Serial No. 44,085 entitled Window-Cleaning Device, now abandoned, and of which this application is a continuation-in-part, may be modified in certain novel respects to improve the operating characteristics thereof. Thus, for example, improved wheel or bearing means may be provided according to the invention to reduce the frictional resistance to starting of the members in any given direction and to impart greater smoothness and efficiency to the cleaning operation on vertical surfaces. These wheel means are provided according to the invention with two sets of bearings adapted to accommodate thrust in two mutually perpendicular directions, one parallel to the plane of movement of the members and the other normal thereto.

It has also been found that for any given wheel or bearing suspension a certain optimum magnetic coupling force should obtain between the companion members and that a magnetic coupling properly established for a pane of one thickness will necessarily vary from this optimum value on a pane of different thickness. If the thickness of the pane is increased, for example, or if the magnetic coupling otherwise becomes weakened, the follower member may be unable to duplicate effectively all movements of the leader member. If the thickness of the pane is decreased, hence strengthening the magnetic coupling by virtue of the fact that the magnetic members are closer together, the bearings may become overloaded. Accordingly, the invention provides an improved magnetic coupling arrangement whereby the coupling forces may be adjusted to accommodate panes of various thickness and otherwise compensate for changes in the strength of the magnetic coupling over the work life of the device.

The efficient cleaning of window panes may involve the use of at least two cleaning implements such, for example, as a wetted brush and a squeegee used one after the other. Accordingly, the invention provides magnetically coupled carrier members together with cleaning implements of different types adapted to be inter-

2

changeably mounted on the carrier members so that only one pair of carrier members need be provided for a complete cleaning operation. The cleaning implements must be designed to operate effectively when displaced over the window pane in accordance with the movements of wheeled carrier members. According to the invention a brush attachment is provided which may be detachably mounted on a carrier member and which carries a supply of water in addition to that which may be entrained in the bristles of the brush. In the case of the squeegee it is necessary that the squeegee engage the working surface in only one direction of movement and according to the invention means are provided for raising the squeegee blade from the surface of the window pane when the movement of the carrier member is in the wrong direction with respect to the inclination of the squeegee blade and for properly engaging the blade with the surface when the movement is in the proper direction.

The invention may be better understood from the following description of one of a preferred embodiment thereof taken in conjunction with the accompanying drawings in which

Fig. 1 is a view in side elevation showing a pair of substantially similar leader and follower carrier members magnetically coupled on opposite sides of a window pane, the leader carrier being shown in cross section taken on the line 1—1 of Fig. 2 looking in the direction of the arrows;

Fig. 2 is a view of the under-side of the leader carrier looking in the direction of the arrows 2—2 of Fig. 1;

Fig. 3 is a view in side elevation of a portion of one of the wheel assemblies of the carrier members;

Fig. 4 is a view of the under-side of the component parts shown in Fig. 3;

Fig. 5 is a view in cross section taken on the line 5—5 of Fig. 4 looking in the direction of the arrows;

Fig. 6 is a plan view of one of the carrier members showing a squeegee attachment affixed thereto;

Fig. 7 is a side view of the squeegee attachment shown in Fig. 6;

Fig. 8 is a plan view of a brush attachment adapted to be detachably secured to the carrier members; and

Fig. 9 is an end view of the brush attachment shown in Fig. 8.

Referring to the drawings and to Figs. 1—5 in particular there is shown a window-cleaning device formed according to the invention compris-

ing broadly two companion carrier members or vehicles 10 and 11 hereinafter called the leader and follower carriers respectively. The leader and follower carriers are magnetically coupled by means described in detail below so that they may be placed on opposite surfaces of a window pane W and the movements of the leader over one surface will be duplicated by the follower over the other surface. The leader and follower carriers 10 and 11 in the illustrated embodiment of the invention are substantially alike and only the leader carrier need be described in detail herein, with like components of the follower carrier being designated with like primed reference numerals.

The leader carrier 10 includes a housing shell 12 of plastic or the like which may be formed with a handle 13 on its outer surface. The handle is formed with a hole 14 by means of which a safety cord or tape may be attached thereto, the other end of the cord being attached to a handle 13' formed on the follower carrier 11. The handle 13 on the leader should afford a comfortable grip for the operator, whereas the handle 13' of the follower, which is not used once the carriers are in position, may be of less elaborate design.

The housing shell 12 is formed on its under-side with four rectangular openings 16 (Fig. 2) at its corners and four substantially conical recesses 17 comprising part of the wheel assemblies described below.

Received within the housing shell 12 for limited adjusting movement normal to the pane W is a shaped magnetic core 18 formed with four depending pole pieces 19 which extend through the openings 16 in the housing and which are properly polarized to attract the corresponding core 18'. The cores 18 and 18' may both be formed of a good permanent magnet material such as Alnico 5, for example, or alternatively one core may be a permanent magnet and the other a magnetically attractive member of soft iron, for example, which is not permanently magnetized. To adjust the position of the core 18 so that the gap between its pole pieces 19 and the corresponding pole pieces 19' of the follower member, an adjusting screw 20 is provided which is anchored in the core 18. The free end of the screw 20 is received in an aperture 21 formed in the housing shell 12, and an internally threaded adjusting knob 22 is threaded on the screw 20. A resilient spring member 23 and washer 24 are interposed between the core and the housing to apply tension to the screw to hold the core 18 yieldably in position.

A pointer 22a may be formed on the knob 22 and cooperating calibrations 22b (Fig. 6) may be formed on the housing to afford an indication of the relative position of the core within the housing. The core in the follower may be similarly adjustable or alternatively only the core in one of the carriers may be adjustable.

Received in each of the four recesses 17 formed in the under-side of the housing is a wheel assembly indicated generally by the numeral 25 and shown in Figs. 1 and 3-5. Each of the four wheel assemblies 25 in each carrier is identical and only one need be described in detail herein. As shown in Fig. 1 in cross section, the wheel assembly includes a circular rotatory member 26 formed with two annular channels or indentations 27 and 28 which in cooperation with corresponding annular channels or indentations 29 and 30 respectively formed in the recess 17 com-

prise outer and inner ball-bearing races. The inner and outer ball-bearing races are fitted with rings of bearing balls 31 and 32 respectively. The rotatory member 26 is thus mounted to rotate freely about a central axis normal to the plane of the surface W and a retaining ring or washer 33 is provided to hold the member 26 against its bearings. The retaining washer 33 also cooperates with the body of the member 26 to shield the rings of ball-bearings 31 and 32 from dirt and the like, but may let in the water as a lubricant.

The ball-bearings 31, operating in the inner race defined by the opposing channels 28-30 are arranged to accommodate thrust normal to the plane of the surface W and the ball-bearings 32 in the outer race 27-29 are arranged to accommodate thrust parallel to the plane of the window W.

Each of the circular rotatory members 26 is formed eccentrically of its axis of rotation with a recess 34 which receives a wheel 35 rotatively supported on an axle 36 clamped or otherwise secured in the member 26. Each of the wheels 35 may be fitted with a semi-hard rubber tire 37 over a web formed of a suitable light material such as aluminium or plastic, for example. Each wheel may also be provided with a sleeve or ball type bearing to facilitate free rotary movement. Thus each wheel assembly comprises a freely rotatable wheel carried in a novel self-aligning carriage journaled in the carrier housing and particularly adapted to operate on a vertical surface. It will be understood, for example, that the plane parallel to the surface W and containing the ring of ball-bearings 32, which accept thrust parallel to the pane W, passes very close to the axes of rotation of the wheels 35. Thus binding of the bearings 31 is prevented and the members 26 are free to align themselves quickly without canting with the random directions of movement of the carrier. This is particularly important in minimizing starting friction, which might break the magnetic coupling between the carriers.

Referring now to Figs. 6-9 there are shown two detachable cleaning implements comprising a squeegee attachment 38 and a brush attachment 39 adaptable to be interchangeably received on the carriers for working equipment with the surfaces of the pane W. It will be understood, of course, that a typical cleaning device might comprise two carrier members, two brush attachments and two squeegee attachments.

There is shown in Figs. 6 and 7 the squeegee attachment 38 which comprises a rectangular frame having side rails 40 and 41 joined by narrow transverse rails 42a and 42b. The frame is thus formed with a central opening which receives the carrier, the frame being adapted to engage a pair of rims 43 and 44 formed on either side of the carrier housing. The carrier may also be formed on either side with rounded extensions 45 and 46 which engage the rails 40 and 41 respectively in a frictional clamp. If desired, a spring detent or other latch means may be provided to secure the frame on the carrier.

The side rails 40 and 41 are each formed with downwardly inclined slots 47 (Fig. 7) each having an enlarged opening 48 at the inner end. A transverse spring clamp 49, formed with lugs 50, is received in the slots 47 and is pivotally attached at 51 to the rails 40 and 42 for limited pivotal movement about an axis parallel to the surface W.

The pivoted spring clamp 49 is adapted to embrace a rubber squeegee blade 52 having an enlarged or beaded edge 52a, which may be encased in a metal guard 52b. The blade may be fitted in the clamp by inserting it endwise therein and a leaf spring detent 54 formed with a knob 53 may be provided on the clamp to assist in holding the blade in position.

An automatic squeegee blade actuating mechanism is provided according to the invention in order that the blade 52 may be brought into operative engagement with the surface W only when the carrier and squeegee are moved in the proper direction with respect to the angle of inclination of the blade. In this fashion a window pane may be squeegeed by several strokes of the carrier without streaking and without introducing additional friction between the blade 52 and the surface W as would be caused by moving a squeegee in the direction of its inclination.

To effect unidirectional action of the blade, a driving linkage is provided comprising a pair of wheels 55 and 56 journalled in the rails 40 and 41 respectively and adapted to roll upon the surface W.

A hub portion 55a (Fig. 7) is formed on the wheel 55 and cables or flexible bands 57 are strung between the hub and the squeegee as follows. One cable 57 is attached at one of its ends to a lug 58 formed on the upper surface of the clamp, and passes upwardly over a smooth pin or pulley 59, over a similar pulley on the pivot 51 and then to the hub 55a to which it is secured by a rivet 60a. The other cable 57 is attached to the hub 55a by a rivet 60b and passes about a pin or pulley 61 to attach to a lug 62 formed on the under-side of the clamp 49. In operation as the attachment is moved over the surface W in the direction of the arrow in Fig. 7, the wheel 55 will be rotated slightly in a counter-clockwise direction causing the hub 55a to apply tension to the cable connected to the lug 62 and slackening off the cable connected to the lug 58, thereby pulling the squeegee blade 52 instantaneously into working engagement with the surface W. Movement of the squeegee attachment in the other direction will apply tension to the cable connected to the lug 58 and will slack off the cable connected to the lug 62, thereby pivoting the clamp and squeegee blade in a counterclockwise direction to raise the blade from the surface. In this fashion a carrier, having the squeegee attachment affixed thereto, may be moved to and fro on the wet pane W with the squeegee engaging the surface in response to movement in one direction only.

The detachable brush attachment 39, as shown in Figs. 8 and 9, comprises a rectangular frame 63 formed with a central opening 64 by means of which it may be fitted on a carrier member to engage the rims 43 and 44. A pair of detents or locking lugs 65 may be provided on the frame to engage the extensions 45 and 46 of the carrier to secure the attachment in place. A rectangular strip 66, in which bristles 67 are embedded, is attached to the rectangular frame 63 with the bristles 67 splaying obliquely outwardly as shown in Fig. 9 to engage the surface W. This arrangement of the bristles decreases friction and generally improves the cleaning action of the brush. A sponge liner or insert 67a may be provided between the bristles and the frame for carrying an additional supply of water or other cleaning media, and a second sponge liner 67b may be

provided which may engage the surface W to supplement the cleaning action of the brush.

In conformance with standard practice the cleaning cycle for windows comprises first using the brush attachment wetted with the cleaning medium followed by the squeegee attachment.

The particular form of the invention herein described and illustrated in the accompanying drawings is presented merely as an example of how the invention may be applied. Thus, for example, it will be understood that it is the magnetically supported follower carrier which is particularly critical with respect to its wheel means and that the novel and effective wheel assembly disclosed herein may be used for the follower and a simple and less efficient wheel arrangement may be used for the leader carrier which is under the direct control of the operator. Also the detachable cleaning implements may be designed to facilitate the cleaning of window panes by the use of cleaning media other than water. Thus, for example, various chemical or drycleaning methods may be used and it will be understood that the carrier members are capable of operating on wet or dry surfaces alike. Other forms and embodiments of the invention coming within the proper scope of the appended claims will readily suggest themselves to those skilled in the art.

I claim:

1. In a cleaning device for operating on both surfaces of a window pane simultaneously comprising a pair of carrier members adapted to be disposed on opposite surfaces of the pane, and magnetic means for maintaining said carriers in corresponding positions on opposite surfaces of the pane so that one carrier as a follower on one surface of the pane may duplicate the movement of the other carrier as a leader on the other surface of the pane, the improvement comprising a plurality of wheel assemblies for at least one of said carriers, each of said wheel assemblies including a rotary member having an axis of rotation normal to the plane of the window pane, a wheel journalled in said rotary member, first bearing means between said rotary member and said carrier for accepting thrust in a direction normal to the pane, and second bearing means between the rotary member and the carrier for accepting thrust in all directions parallel to the pane, said wheel being disposed eccentrically of the axis of rotation of said member, the axis of rotation of the wheel being contained in a plane substantially parallel to that of the window pane, said second bearing means being contained in a plane also parallel to the window pane and closely adjacent the plane containing the axis of rotation of said wheel.

2. In a cleaning device for operating on both surfaces of a window pane, comprising a pair of carrier members adapted to be disposed on opposite surfaces of a window pane, and each of said carriers including a housing, magnetic means supported in said housing, the improvement comprising a plurality of wheel assemblies carried by said housing, each assembly including a circular rotary member journalled in said housing for rotary movement about an axis normal to the plane of the pane, first bearing means between said rotary member and housing for accepting thrust in a direction normal to the plane and facilitating free rotary movement of said member, annular second bearing means between said housing and rotary member for accepting thrust between the rotary member and the housing in all directions

parallel to the pane, and wheel means journaled in said member eccentrically of the axis of rotation thereof for engaging the surface of the window pane, the radius of said annular second bearing means exceeding the radius of the said wheel plus the amount of eccentricity representing the spacing of the center of rotation of the wheel from the axis of rotation of the rotary member.

3. In a cleaning device for operating on both surfaces of a window pane and the like, comprising a pair of carrier members of substantially similar design adapted to be disposed on opposite surfaces of the pane for concurrent movement thereupon, at least one of said members comprising a housing shell having an under surface with a plurality of openings therein, and a magnetized core member movably received within said housing and having a plurality of pole-pieces received in certain of said openings in the housing, the improvement comprising a plurality of wheel assemblies received in the other of said openings, each of said wheel assemblies comprising wall means forming a conical recess, said recess having first and second spaced apart annular channels formed therein, said channels being contained in spaced apart planes parallel to the surface of the pane, a rotary insert member received in said conical recess and having formed therein first and second annular channels corresponding to and opposing the said first and second channels formed in the recess and forming first and second ball-bearing races, first and second rings of ball-bearings disposed in each of said races, the first of the rings of ball-bearings being adapted to accept thrust in a direction normal to the pane and the second ring accepting thrust in all directions parallel thereto, retainer means for holding said rotary member in the recess and a wheel rotatably journaled in said rotary insert member eccentrically of the axis of rotation thereon, the axis of rotation of the wheel being parallel to and closely adjacent the plane of said second ring of ball-bearings.

4. A cleaning device as set forth in claim 3, including a screw member anchored in said magnetic core member, said housing being formed with an opening in the outer surface thereof to receive the outer end of said screw, resilient spring means interposed between the housing and the magnetic core member to urge the latter in the direction of the pane, and an adjusting knob attached to said screw on the outer surface of the housing, and cooperative calibration and pointer means formed on said knob and housing for indicating the approximate position of said magnetic core member with respect to the surface of the pane.

5. A cleaning device for movement over the surface of a window pane and the like, comprising a shell portion, a flat bottom portion on the shell adapted to be disposed adjacent the surface to be cleaned parallel thereto and formed with a plurality of openings, magnetic means received within the shell and having a plurality of pole pieces projecting through said openings, means

for displacing said magnetic means in adjusting movement within the shell to vary the extent of the projection of the pole pieces through the openings, wall means carried by the bottom portion and defining a plurality of recesses disposed among the projecting pole pieces, said recesses being formed with annular bearing races having surfaces both parallel and normal to the surface to be cleaned, and castor wheel means received within said recesses, with the axes of the wheel means being disposed closely adjacent the plane of the bottom portion and within the circumference of at least one of the said bearing races.

6. A cleaning device for movement over the surface of a window pane and the like, comprising a substantially rectangular shell portion, a flat bottom portion on the shell adapted to be disposed adjacent the surface to be cleaned and parallel thereto, said bottom portion being formed at its respective corners with openings, inwardly convergent wall means carried by the bottom portion forming a plurality of frustoconical recesses therein, magnetic means mounted within the shell portion having a plurality of pole pieces projecting through said openings, said magnetic means being constrained by the inner walls of the shell to move normal to the surface to be cleaned, screw means reacting between the shell portion and the magnetic means for adjusting the position of the magnetic means within the shell to vary the spacings of the pole pieces from the surface to be cleaned, means forming at least two annular bearing races in each of the said recesses and spaced different distances from the surface to be cleaned, the innermost race being of smaller diameter than the outer race and each of said races having surfaces parallel and normal to the surface to be cleaned, castor wheel means received in the recesses comprising a circular carriage portion having bearing races for cooperating with those of the recesses, bearing balls in said races, and a wheel rotatably mounted on the carriage and having an axle which is disposed parallel to the surface to be cleaned and disposed closely adjacent the plane of the said bottom portion and within the circumference of the outermost bearing race.

7. A cleaning device as set forth in claim 6, said shell portion being formed on its outside surface with lateral extensions for carrying cleaning attachments.
